UNITED STATES PATENT OFFICE.

FREDERICK W. ANDREW, OF BROOKLYN, NEW YORK, ASSIGNOR, BY MESNE ASSIGNMENTS, TO EISEMANN MAGNETO CORPORATION, OF BROOKLYN, NEW YORK, A CORPORATION OF NEW YORK.

IMPULSE-STARTER.

1,342,199.

Specification of Letters Patent.

Patented June 1, 1920.

Application filed November 18, 1918. Serial No. 263,034.

To all whom it may concern:

Be it known that I, FREDERICK WILLIAM ANDREW, a citizen of the United States, and a resident of the city of New York, borough 5 of Brooklyn, county of Kings, and State of New York, have invented certain new and useful Improvements in Impulse-Starters, whereof the following is a full, clear, and exact specification, reference being had 10 to the accompanying drawings, wherein—

Figure 1 is the front view of a magneto, prepared for the mounting thereon of an impulse starter constructed according to my invention;

15 Fig. 2 is a similar view showing the impulse starter mounted on the armature shaft, a part of the casing, constituting the driving part, being broken off to disclose the spring 50 yieldingly connecting the driving with the driven part;

Fig. 3 is a rear view of the driven part of the impulse starter, showing the mechanism 55 engaging with the stop, shown in Fig. 1, for holding the driven part against rotation

20 when, on starting, the driving part is rotated in advance of it;

Fig. 4 is a view similar to Fig. 3, showing the parts of the mechanism in their relative 60 positions at the moment of release of the driven part;

Fig. 5 is a front view of the driven part;

Fig. 6 is a rear view of the driving member;

Fig. 7 a sectional view of the complete 35 impulse starter shown as mounted on the magneto shaft.

My invention relates to devices known in the art as "impulse starters," by means of which a rapid rotatory motion is imparted 40 to the armature of a magneto at the moment of starting an internal combustion engine to produce a spark of sufficient intensity to ignite the explosive charge in the cylinder of the engine. These impulse starters are usually composed of a driven 45 part, fixed to the magneto shaft, a driving part rotatably mounted thereon, and of a spring situated so as to be tensioned by rotating the driving part in advance of the driven part; in addition some mechanism 50 is provided for arresting the motion of the driven part (and of the magneto shaft) when the driving part is to be rotated in

advance of the driven part, and for releasing it, whereupon the spring, reacting, propels 55 the driven part, and the magneto shaft, rapidly through a part of its revolution, whereby a spark of sufficient intensity to ignite the explosive charge in the cylinder 60 of the engine is produced.

The mechanism for holding the driven part of the impulse starter against rotation, when the driving part is rotated in advance of it, and for again releasing it, is in all constructions of this device, heretofore 65 known, partly or largely housed within the impulse starter, and therefore, not accessible for inspection and repair without taking the impulse starter apart. This arrangement is productive of difficulties when the 70 vehicle is on the road, and some part of the mechanism breaks, or the parts get disarranged. Another objectionable feature of the impulse starters heretofore constructed was the uncertain or improper action of the 75 centrifugal member which temporarily held the driven part by engaging a fixed stop.

The object of my invention is to improve the construction of these devices, by so devising the mechanism for holding and releasing the driven part, that it may be applied on the outside of the parts of the impulse starter, readily accessible for inspection, adjustment and repair, by providing a centrifugal member which is always 80 85 reliable in operation, as subsequently more fully explained, and by so constructing many of the parts that they may be made out of sheet metal, thereby materially decreasing the cost of manufacture. My invention consists in devising an impulse 90 starter, embodying improvements whereby the stated objects of my invention are attained, and of which an example is shown in the drawings and hereinafter described. 95

The part, designated by the reference numeral 11 in the drawings, is the driven part of the impulse starter, made in the shape of a circular disk, having an annular flange 13, a peripheral recess 14, and a forwardly extending hub 15, is fitted upon, and keyed to, the end of the magneto shaft 12. The driving part 16 is shaped as a circular casing, wherein the spiral spring 17 is housed. It is centrally perforated, the 105 edge 16^c of the perforation being fitted onto

the hub 15 of the driven part 11, and the rim 16^a of the driving part onto its annular flange 13. The teeth, or projections, 31 on the driving part 16 are provided for joining it to a gear-wheel or other device, whereby rotatory motion is transmitted to the driving part from the shaft of the engine.

The disk 11 and the hub 15 are preferably made separate, as shown in Fig. 7.

- 10 The disk is rigidly fixed upon the hub and held thereon in any suitable way, as by the flanges 15^a and 15^b. It is obvious from the illustration in Fig. 7, that the parts 11 and 16 may be formed out of sheet metal, thereby decreasing the cost of manufacture. The cup-shaped driving part 16 has fixed thereon the sleeve 15^c adapted to fit against the hub 15. The recess formed by the hub 15 and the sleeve 15^c accommodates the nut 15^d, by means of which the closed casing formed by the parts 15 and 11 is securely held on the magneto shaft 12. As seen from Fig. 7, the end of the magneto shaft 12 is substantially flush with the outer face of the driving member 16.

25 The driving and the driven parts of the impulse starter are yieldingly connected by the spring 17. One end of this spring 17 is set in the notch 18, made in the hub 15 of the driven part 11, and the other is hooked to the lug 19, secured to the circumferential rim 16^c of the driving part 16. Thus, when the driving part (16) is rotated, while the driven part is held in a fixed position, the spring 17 is tensioned by having its coils wound tight, and set to react when the driven member is released. The force propelling the driving member 16 prevents its being rotated reversely, and thus the reaction of the spring is exerted upon the driven member, throwing it, and the magneto shaft, to which the driven member is secured, forward at high speed of rotation, whereby a spark of sufficient intensity to ignite the explosive charge in the cylinder of the engine is produced.

30 The tooth 16^b, formed on the rim 16^a of the driving part 16 engages the shoulder 14^a of the recess 14 of the driven part 11, when the parts are set together, as shown in Fig. 3, this normal position of the parts referred to being maintained by the spring 17. The spring 17 has an initial tension when the driving and driven parts are first assembled, and this initial tension holds the tooth 16^b of the driving part 16 in contact with the shoulder 16^c of the driven part 11. As seen from Figs. 6 and 7, the chamber formed by the casing 16 and the disk 11, in which the coil spring 17 is housed, is free from any operative part or member projecting into it, so that the spring may occupy practically the entire chamber. This permits the use of a spring of sufficient size and strength. This spring must be strong

enough to form at all times the driving coupling or connection between the engine and the magneto.

One or two (or more) cams 29 are made on the rim 16^a of the driving part for acting on the mechanism, whereby the driven part is held against rotating when the impulse starter is set for action, the number of cams corresponding to the number of swinging pawls 21, mounted on the driven part.

10 The mechanism for holding the driven part against rotation when the driving part is to be rotated in advance of it, comprises the oscillating pawls 21, pivoted at 22 to the rear-side of the driven part 11, the guide-lugs 23, secured to the rear-side of the driven part 11 in position to engage the free ends of the pawls 21; the teeth 24 on the free ends of the pawls 21, and the stop 25, suitably fixed to the magneto casing 26 in position to be engaged by the tooth 24 of one of the pawls 21, when the engine is to be started. Pawls 21 swing freely on their pivots 22, they are driven outwardly by centrifugal force when the magneto is driven at or above its normal speed, and drop when the magneto stands still. The extent of their movement is, however, limited, inwardly by their forwardly bent ends 27 contacting with the rim 16^a of the driving member, and outwardly by the teeth 24 contacting with the lugs 23. The position they assume when the engine stops, and the impulse starter is turned, is shown in Fig. 3. 100 In this position the tooth 24 of one of the levers 21 is in line with the stop 25 and in engagement therewith. Only one of the pawls 21 and appurtenances thereof are required; the second of the two shown in 105 the drawings is provided to obtain a second impulse rapidly following the first, to explode the charge in the next cylinder of the engine, if the first should fail to start the engine.

110 The stop 25 is shown in Fig. 1 of the drawings as part of the bracket 32, secured to the frame of the magneto by being affixed to the base thereof by screws 33. It may, however, as well be secured to the casing, or 115 otherwise fixed in its place, the only requirement being that it should be fixed so that when the magneto runs at or above its predetermined normal speed, whereby the pawls 21 are moved outwardly, the teeth 24 will 120 not come in contact therewith, but should be in the path of the teeth 24, when the magneto stops running. Then by turning the crank-shaft of the engine, the impulse starter is turned with the shaft of the magneto, until the tooth of one of the pawls 21 abuts against the stop 25, whereby the further rotatory motion of the driven part, and of the magneto shaft, to which it is affixed, is arrested. The driving part is then ro- 130

tated alone, in advance of the driven part, until one of the cams 29 comes in contact with the forwardly bent free end of the pawl 21 which is then resting on the rim 16^a of the driving part 16. The cam 29 then lifts the pawl 21 and thereby withdraws the tooth 24 from its engagement with the stop 25, the driven part is released and the spring 17, tensioned by the forward movement of the driving part, reacts and drives the driven part, and the rotatory part of the magneto, at a rapid pace through a part of its revolution, thus producing the impulse and a spark of sufficient intensity to ignite the compressed explosive charge in one of the cylinders of the engine, and thereby the engine is started. Thereafter, the impulse starter acts as a coupling connecting the magneto shaft with the gear driven from the engine.

The moment of release of the driven part 11 by one of the cams 29 on the driving part 16 occurs just before the tooth 16^b reaches the end of the recess 14, as indicated in Fig. 4. The driven part 11 is thereupon put in motion rapidly by the tensioned spring 17 until the shoulder 14^c (which forms one end of the recess 14 on the driven part 11) strikes the edge 16^d of the tooth 16^b on the driving part 16. This operation of the impulse starter is repeated until the speed of the armature shaft is sufficient to cause the pawls 21 to fly out under the action of centrifugal force, thereby clearing the teeth 24 of the fixed stop 25. The length of the recess 14 is sufficient to allow the tooth 16^b to travel until the moment of kick-off, or release of the driven part 11. At this moment there should be a slight clearance, as indicated at *a* in Fig. 4, between the forward edge 16^e of the tooth 16^b and the shoulder or end 14^b of the recess 14. Obviously, the length of the recess 14 may be varied and will depend upon the length of the arc of travel of the cam 29 from its normal or rest position (as shown in Fig. 3) to the position of release (as shown in Fig. 4).

It will be observed that the pawls 21 are free from all objectionable spring connections and are controlled entirely by gravity. The centrifugal force acting on the pawls has no spring pressure to counteract, as in prior constructions, but has only to overcome the effect of gravity. To insure a steady, regular and dependable action, the pawls 21 are made of such a length that the free weighted end, which carries the tooth 24 and the projection 27, operates through a long lever arm, of which the fulcrum is the pivot point 22. To accommodate this long pawl on the driven part 11, the pawl is curved and extends over an arc of about ninety degrees, as clearly shown in Figs. 3 and 4. A pawl of this construc-

tion and arrangement acts with certainty and requires no regulation or adjustment. In prior impulse starters, where a spring is associated with the centrifugal member, great care is required to adjust the spring in each starter, whereas in my construction the long gravity pawls act alike in all starters.

In the preferred embodiment of my invention, the pawls 21 are mounted to trail, as distinguished from leading pawls. That is to say, assuming the parts to rotate in the direction indicated by the arrow in Figs. 3 and 4, the pivot points 22 are in the lead and the free ends, which carry the teeth 24, are in the rear, or trail. I have demonstrated by actual tests that a trailing pawl performs its intended functions more satisfactorily than a leading pawl, where the free or active end is in the direction of rotation of the part on which the pawl is mounted.

I claim as my invention:

1. An impulse starter comprising a disk, having a hub adapted to be fixed onto the shaft of a magneto, and a peripherical recess; a centrally perforated casing, rotatably mounted upon the disk, and having a portion of its rim extended into the peripherical recess of the disk, a spring having one end connected to the disk, and the other to the casing, means operatively connecting the casing with the shaft of the engine, a fixed stop; means movably mounted on the disk and adapted to drop in engagement with the stop when the engine stops; and means on the casing, adapted to engage the means, movably mounted on the disk, when the said casing is rotated in advance of it, thereby setting the disk, and the magneto shaft, free to be rotated by the spring and by the casing.

2. An impulse starter comprising a disk, having a hub adapted to be fixed onto the shaft of a magneto and a peripherical recess; a centrally perforated casing, rotatably mounted upon the disk, and having a portion of its rim extended into the peripherical recess of the disk, a coiled spring having one end attached to the disk, and the other to the casing, means operatively connecting the casing with the shaft of the engine, an abutment movably mounted on the rear-side of the disk, facing the magneto, and having an arm extended over the casing, a stop set in position to engage the abutment, thereby holding the disk against rotation; means on the casing adapted to contact with the arm of the abutment, and to move the abutment out of engagement with the stop, when the casing is rotated in advance of the disk, thereby releasing the disk to rotate with the casing.

3. An impulse starter comprising a disk adapted to be fixed onto the shaft of a magneto and having a peripherical recess, a

cylindrical casing, rotatably mounted upon the disk, and having a portion extended into the peripherical recess of the disk, a coiled spring, having one end attached to the disk, 5 and the other to the casing, means operatively connecting the casing with the shaft of the engine, a swinging pawl pivoted to the disk and having its free end offset to extend over the edge of the disk, means for guiding 10 and limiting the movements of the pawl, a stop set in position to engage the pawl when in receded position, a cam on the rim of the casing in position to contact with the offset free end of the pawl when the casing is rotated to a predetermined extent in advance 15 of the disk, and to move the pawl, thereby disengaging it from the stop and setting the disk free to rotate with the casing.

4. An impulse starter comprising a driven 20 part adapted to be fixed on the shaft of a magneto, a driving part adjacent to and concentric with said driven part, a spring set between the driven part and the driving part, so as to be tensioned by rotating the 25 driving part in advance of the driven part, a gravity pawl pivoted on the driven part and extending over an arc of about ninety degrees, a tooth on the free end of said pawl, a stop fixed in the path of said tooth to be 30 engaged thereby for holding the driven part against rotation, means on the driving part adapted to act on said pawl when the driving part is rotated in advance of the driven part and to disengage the pawl from the 35 stop, and means for operatively connecting the driving part with the rotating part of the engine.

5. An impulse starter comprising a driven 40 part adapted to be fixed on the shaft of the magneto, a driving part mounted adjacent to and concentric with the driven part, a coiled spring yieldingly connecting the driven part with the driving part, means operatively connecting the driving part with 45 the shaft of the engine, a swinging gravity pawl mounted on the rear side of the driven part facing the magneto, a tooth at the free end of said pawl, a stop set in position to engage said tooth and thereby hold the 50 driven part against rotation, said pawl being mounted so that the free end thereof trails when the driven part is rotated, means movable with the driving part for engaging said pawl when the driving part is rotated 55 in advance of the driven part and thereby disengaging said tooth from said stop, whereby the driven part is set free to rotate with the driving part.

6. An impulse starter comprising a driven 60 part, adapted to be fixed on the shaft of the magneto, a driving part mounted adjacent to and concentric with the driven part, a spring yieldingly connecting the driven part with the driving part, and so as to be tensioned when the driving part is rotated in

advance of the driven part; means operatively connecting the driving part with the shaft of the engine, swinging pawls pivoted to the rear-side of the driven part, facing the magneto, and having their free 70 ends offset to extend forward over the edge of the driven part, means for guiding and limiting the movements of the pawls, a stop set in position to engage one of the swinging pawls when swung inwardly, thus holding the driven part against rotation, cams on the driving part in position to contact with the offset end of the pawl engaged by the stop when the driving part is rotated to a predetermined point in advance of the 80 driven part, thereby swinging the pawl outwardly and disengaging it from the stop.

7. A flexible coupling for transmitting 85 rotatory motion from the shaft of an internal combustion engine to the shaft of a magneto, the coupling comprising a driven part, adapted to be fixed on the shaft of the magneto and having a peripheral recess, a driving part mounted adjacent to and concentric with the driven part, and having a 90 projection extending into the recess in the driven part, a coiled spring having one end attached to the driven and the other to the driving part, and means operatively connecting the driving part with the shaft of 95 the engine.

8. An impulse starter comprising a disk 100 fixed on the shaft of a magneto, a casing mounted adjacent to and concentric with said disk, said casing and said disk forming a chamber, a coil spring arranged in said chamber and of proportions to practically fill the same, means for connecting one end of said spring with said disk and the other end with said casing, co-operative abutments 105 on said casing and said disk for normally holding these two parts in predetermined relation to each other and for limiting the extent of relative movement of said parts, said abutments being independent of said connecting means, a fixed stop, a pivoted gravity member mounted on the outside of said disk, where it is readily accessible and adapted to drop into engagement with said stop when the engine stops, means outside 110 of said spring chamber and movable with said casing for engaging said member when said casing is rotated in advance of said disk, thereby setting said disk and the magneto shaft free to rotate with the casing, 115 and means for operatively connecting the casing with the engine.

9. An impulse starter comprising a driven 120 part adapted to be fixed on the shaft of a magneto, a driving part mounted adjacent to and concentric with the driven part, a spring connecting the driven and the driving part for rotating the driving part in advance of the driven part, a gravity pawl pivoted on the driven part and extending 125

- over an arc of about ninety degrees, a tooth on the free end of said pawl, a stop fixed in the path of said tooth to be engaged thereby for holding the driven part against 5 rotation, said pawl being mounted so that the free end thereof trails when the driven part is rotated, means movable with the driving part for engaging said pawl when the driving part is rotated in advance of the 10 driven part and thereby disengaging said tooth from said stop, whereby the driven part is set free to rotate with the driving part, and means for operatively connecting the driving part with the engine.
- 15 10. An impulse starter comprising a driven part adapted to be fixed on the shaft of a magneto, a driving part mounted adjacent to and concentric with the driven part, a spring connecting the driven part with 20 the driving part, so as to be tensioned when the driving part is rotated in advance of the driven part, means for operatively connecting the driving part with the shaft of the engine, a gravity pawl pivoted to the out- 25 side of the driven part facing the magneto, so as to be readily accessible, the free end of said pawl being offset to extend over the edge of the driven part, a stop set in position to engage said pawl when swung in- 30 wardly and thereby hold the driven part against rotation, and a cam on the outside of the driven part in position to engage said offset and thereby disengage said pawl from 35 said stop when the driving part is rotated a predetermined amount in advance of the driven part.
11. In an impulse starter, a hub adapted to be fixed on the shaft of a magneto, a disk separate from said hub and rigidly mounted 40 thereon, a cup-shaped driving member rotatably supported on said hub and said disk, said driving member and said disk forming a closed casing, a coil spring arranged within said casing for operatively connecting 45 said driving member with said disk, a fixed stop, a movable member carried by said disk for engaging said stop to hold the disk against rotation, means located outside of 50 said casing and movable with said driving member for actuating said holding member to release said disk when said driving member is rotated in advance of said disk, and means for operatively connecting said driving member with the shaft of the engine.
- 55 12. In an impulse starter, a cup-shaped member and a disk-shaped member mounted on the magneto shaft and forming a closed casing rotatable with said shaft, said mem- 60 bers being rotatable relatively to each other, a spring in said casing for operatively con-
- necting said members together, a fixed stop, a swinging pawl on the outside of one of said members to engage said stop and thereby hold said member against rotation, said last named member being the driven mem- 65 ber and fixed on the magneto shaft to rotate therewith, said pawl being provided with an off-set portion extending on the outside of said casing, cam means on the outside of the other or driving member for en- 70 gaging said off-set portion and releasing the driven member when the driving member is rotated in advance of the driven member, and means for operatively connecting the driving member with the engine shaft. 75
13. In an impulse starter, a hub adapted to be fixed on the shaft of a magneto, a disk fixed on said hub, a cup-shaped driving member rotatably supported on said hub and said disk, said cup-shaped member and said disk forming a closed casing; a central sleeve fixed on said cup-shaped member and fitting against said hub, said sleeve forming a recess into which the magneto shaft projects, a nut on said shaft within 80 said recess to engage said sleeve and thereby hold said casing on said shaft, a spring ar- 85 ranged within said casing for operatively connecting said cup-shaped member with said disk, coöperating means on said disk and said member for determining the nor- 90 mal position of said two parts relatively to each other, a fixed stop, gravity means ar- 95 ranged to engage said stop for holding said disk against rotation, cam means for engag- 95 ing said gravity means to release said disk when said cup-shaped member is rotated in advance of said disk, and means for oper- 100 atively connecting said cup-shaped member with the engine shaft. 100
14. In an impulse starter, a hub adapted to be fixed on the shaft of a magneto, a disk fixed on said hub, a cup-shaped driving member rotatably supported on said hub and disk, said cup-shaped member and said 105 disk forming a closed casing, a spring with- 110 in said casing for operatively connecting said member with said disk, a fixed stop, means on the outside of said disk to engage said stop and thereby hold said disk against 115 rotation, means on the outside of said cup- shaped member for engaging said holding means and releasing the disk when the driv- ing member is rotated in advance of the disk, and means for operatively connecting the driving member with the engine shaft. 115
